METHOD AND MEANS FOR STORING AND
SELECTING RECORDS

Gustav Tauschek, New York, N. Y.

Application March 10, 1933, Serial No. 660,203

22 Claims. (Cl. 179—100.2)

This application is a continuation in part of my application Serial No. 627,458, filed August 4, 1932.

This invention relates to record retaining devices and more particularly to the type in which a plurality of such devices are provided for selection at will.

The main object is to provide an arrangement whereby a great number of record retaining devices may be provided in a small space and to provide the devices of suitable material so that records may be represented thereon by means of electro-magnetic effects.

The conventional arrangement for retaining records which may be obtained at will consists usually of a group of wheels which are rotated to set up a value and then rotated again to represent the value determined by the set-up. Such arrangements require the provision of a large number of wheels occupying considerable space and the employment of suitable operating devices therefor necessitating moving large masses and the objectionable mechanical difficulties increase as the number of groups are increased.

Distinguishing therefrom the present invention utilizes strips or other elements of steel or other magnetizable material each of which records by point by point magnetic effects, and such magnetic effects of all strips are transcribed to represent upon a series of wheels the data previously entered upon the strips. As other and subsequent data are sometimes required provision is made for neutralizing the magnetic effects upon the strips so that other and new data may be represented by the same strips.

The transcription does not necessarily depend upon a series of point magnetizations as differently located points may be magnetized to control differential effects. In addition, there may be superimposed over such magnetized points variations in magnetism effected by variations in electrical resistance determined by sound, such as speech, directed into a transmitter. The various strips thus magnetized may be selected at will for reproduction of the sound effects previously stored in the strips in the form of variations in magnetic effects. The reproduction is preferably effected by the same transmitter which is employed to produce the variable magnetic effects.

The invention is applicable in conjunction with systems for determining the status of an account. Such information is derived by transcribing the magnetic effects upon a selected group of wires, strips or other elements of mag-

netizable material and representing such effects upon a group of wheels. As the amount represented may be changed by a transaction, the change represented by new positions of the wheels is recorded upon the selected group of strips for subsequent representation. Also, if desired, upon such strips there is registered under control of a telephonic device information relative to the account which may be reproduced at will. The latter feature may be used independently of the account representations and is to be construed as an object of the invention.

The invention is illustrated in the drawings in which

Fig. 1 is a view in side elevation, partly fragmentary, of the unit containing the selectable groups of elements which record data by means of magnetic effects.

Fig. 2 is a plan view of the apparatus disclosed in Fig. 1, also partly fragmentary to show more clearly certain parts.

Fig. 3 is a plan view of the unit which is employed to select the groups of record representing elements.

Fig. 4 is an electrical diagram coordinating the two units disclosed in Figs. 1 and 2 with a data representing apparatus or unit.

Fig. 5 is a diagrammatic representation of the operating devices for one of the data representing devices.

The record representing devices are selected by a dial mechanism comprising a dialing plate 10 (Fig. 3) having a series of finger receiving apertures 11. The actuation of the plate 10 by a finger to a position determined by a finger stop piece 12 turns said plate one or more steps depending upon which aperture 11 is employed for the actuation.

Plate 10 is attached to a stud 13 and to said stud is secured an arm 14 and a gear 15. The arm 14 carries a pawl 16 which has an approximately rectangular pin 17 in the plane of a ratchet wheel 18 which is attached to a dentated disk 19, and both wheel 18 and disk 19 are loosely mounted on stud 13. The gear 15 meshes with a pinion 20 to drive a suitable centrifugally controlled governor 21, which forms no part of the present invention.

The dentated disk 19 as it turns one or more steps is adapted to successively close contacts 22 which are normally open.

For example, to select the record representing device "20", as dial 10 is turned three steps clockwise pawl 16 will ratchet over wheel 18 to position the pin 17 to cooperate with the radial edge

of one of the ratchet teeth. When turning dial plate 18 in a clockwise direction a spring 23 connected to a lug 24, which is part of a circular plate 25 also secured to stud 18, will be tensioned so as to restore dial plate 18 to normal when the finger is taken out of the previously engaged aperture 11. In so doing pawl 16 will drive ratchet wheel 18 contraclockwise and disk 19 will successively close contacts 22 three times. 10 When "0" is dialed, contacts 22 will close once only.

15 The record representing devices are contained in a separate controlling unit shown in Figs. 1 and 2 and comprise a baseboard 26 to which is secured a pair of supports 27 and 28 and said supports carry a vertically-movable circular tube of insulating material 29 which has a pair of integral ears 30 and the latter are provided with slots 31 to receive studs 32 which are carried by 20 the supports 27 and 28 in order that the tube may be raised or lowered.

25 Axially aligned with the tube 29 and movable relatively thereto both lengthwise and around its axis, is a rod 40 which at its upper end 33 is circular but beneath the circular portion 33 the rod is made up of a series of ten conical frusta 41 to provide a series of shoulders 42 adapted to be engaged by a pawl 43 pivotally carried by the armature 44 of a magnet 45.

30 Referring to Fig. 4, it will be observed that magnet 45 is connected to the positive line side 46 and from the magnet the circuit extends by wire 47 to closed contacts 48, thence through contacts 22 to the negative line side.

35 If three impulses are transmitted by the dial mechanism pawl 43 will successively step rod 40 upwardly and each successive position as well as the last position will be held by a retaining pawl 51 also coacting with shoulders 42.

40 After the desired longitudinal movement of rod 40 is effected a rotary movement is then given.

45 To this end, referring to Fig. 3, it will be apparent that when lug 24 is shifted by the initial manual positioning of dial plate 18, contacts 53 will close. By a wire 54 (Fig. 4) the circuit extends through such contacts 53 from the positive line side to one side of a magnet 55, the other side being connected to the negative line side 56.

50 When magnet 55 (Fig. 3) is energized it will attract its armature and shift a pawl 58 pivoted thereto so that the latter will move into a notch 57 in a cam disk 59 and is held therein until contacts 53 open when the dial plate returns to normal. When contacts 53 open magnet 55 is de-energized to permit a spring 59 to shift pawl 58 to turn cam disk 59 one step. Such turning of disk 59 brings a cam portion thereof into a position which permits the dropping of the intermediate blade 61 to close contacts 62 and open contacts 48. The shifted position of disk 59 is held by retaining pawl 58 coacting with a notch 64 in said disk 59.

55 As "0" is dialed after a previous dialing has left the contacts 62 closed, contacts 22 are closed only once and the one impulse is directed through contacts 62 (Fig. 4) by wire 65 to magnet 66 and thence to the positive line side 46.

60 The armature 67 of magnet 66 (see Fig. 2) is pivoted at 68 and the armature has pivoted thereto a pawl 69 in cooperation with teeth of a ratchet disk 70 secured to the lower end of the rod 40 (see Fig. 1). Also cooperating with the ratchet disk 70 is a spring urged holding pawl 71 (Fig. 2). Both pawls 69 and 71 are suffi-

ciently long so as to perform their functions in any position of the rod 40 which might have been effected by the first dialing operation. As rod 40 is turned by pawl 69 such action is effected against the tension of a spring 72 one end of which is connected to the periphery of disk 70 (Figs. 1 and 2).

65 The purpose of the axial and rotary motion of rod 40 will now be explained. The upper end of rod 40 passes through a slot 73 (Fig. 1) in table 20 28 so as to be guided by said slot and above the table are eight radially mounted magnets 84, one for each of the eight denominational orders, units to tens of millions. A pair of wire connections, of course, extend from each magnet so as to provide suitable wire connections to said magnets.

70 Considering a single tier, it will be observed that carried by the interior wall of tube 29 are series of strips 78 of magnetizable material such as steel there being provided ten of such strips 20 in a group, and eight groups corresponding in number to the eight denominations.

75 Each strip 78 is sufficiently long, in a longitudinal dimension, so as to receive magnetization at ten different points, so that each strip may 25 represent any numerical digit value. Each strip of a group represents a denominational order as well as a digit value in that order.

80 The strips 78 are grouped in denominations, or as is well known in the art, are interspersed. All 30 the units of the ten record devices are grouped together, all the tens, etc. As each group of each tier contains ten strips 78, corresponding respectively to the digits 0-9, and there are ten tiers to represent records 0-99, the machine provides for 35 100 records or accounts in a minimum of space.

85 Since record "20" was selected the third tier will be correlated with magnets 84 since magnet 45 will receive three impulses. When "0" is dialed the rod 40 will be turned one step and thus the magnets 84 will be shifted from a neutral position so as to be correlated with the eight denominational strips 78 (that is the first strip in each group) which strips represent record "0" in tier #3. It will be understood that the 45 dial 11 will be operated twice in succession, and that the first dialing will effect a selection of a particular tier by a longitudinal movement of the rod 40, while the second dialing will effect the selection of a particular element 78 in each of the 50 eight groups, by a circumferential or rotary motion of the rod 40 and the magnets 84 carried thereby.

90 Assuming that the eight strips have been previously magnetized, each having the same or different number of magnetized points, and it is desired to ascertain the numerical value represented in the selected record device, the following operation is performed.

95 Key 79 (Figs. 3 and 4) is now depressed so as to close contacts 80. Key 79 has an inclined lug 81 coacting with a lug of a slideable detent 82 so as to hold key 79 depressed in the usual manner, and thus retaining contacts 80 closed. When contacts 80 are closed the circuit extends from the negative line side 50 (Fig. 4) through contacts 80 to a magnet 83 and thence by normally closed contacts 74 and wire 85 to the positive line side 46.

100 From Fig. 1 it will be observed that when magnet 83 is energized it attracts its armature 86. The latter carries a stud 87 of insulating material which normally holds the lower blade 88 of contacts 74 upwardly to keep such contacts closed. Therefore, when magnet 83 is energized, 75

it opens its circuit by opening of contacts 14. Pivoted to armature 88 is a pawl 89 coacting with a ratchet wheel 90. A spring 88a holds pawl 89 in ratchet wheel operating position and 5 also elevates armature 88 when magnet 83 is de-energized by opening of contacts 14.

Thus, it will be clear that armature 88 will vibrate a number of times until the circuit to magnet 83 is permanently opened, by means to 10 be presently explained.

To ratchet wheel 90 there is secured a toothed wheel 90a. This wheel coacts with a toothed wheel 90b, which turns twice during one revolution of the wheel 90a. To the wheels 90b and 90 15 there are secured cams 91 and 92 respectively, the periphery of cam 91 coacting with a lower extension of the right ear 30 of tube 29. After rod 40 has been longitudinally positioned to select a record the points of the conical ends 84A of 20 the magnets register with the tops of strips 18 and for each step of rotation of ratchet wheel 90, cam 91 causes the tube 29 to be raised one step so that for ten steps of rotation of ratchet wheel 90 the magnets register with ten successive points 25 of the strips 18. Thus the conical points 84A analyze the strips for determination of magnetized points.

After a quarter of one revolution of cam 92 from the initial position shown in Fig. 1, a projection 93 of a disk 94 secured to cam 92 will, at 30 the tenth position of the magnets 84, engage the upper blade of contacts 95 to close said contacts. Such contacts extend the circuit from the positive line side to one side of a magnet 96 (Fig. 4), 35 the other side being connected to the negative line side 50. When magnet 96 is energized it attracts its armature 97 which is an integral part of the detent plate 82 and as the latter is shifted it releases depressed key 79 to open contacts 80. 40 The circuit to magnet 83 (Fig. 1) is now opened at the tenth analyzing position and operation of pawl 89 thus stops.

By magnetic induction one or more electrical impulses are created in the magnets 84 and in 45 order to register such effects on an accounting device for visual representation the following action takes place. Hereafter, numerical sub-scripts designate denominational orders.

Considering magnet 84₁, it will be observed 50 that in a closed circuit including such magnet are two sets of normally closed contacts 98₁ and 180₁ and a relay magnet 99₁. The magnet 99₁ when energized will close its related contacts 100₁ thereby extending a circuit from the positive line 55 side by wire 85, thence by a wire 101 through closed contacts 100₁, and thence by wire 102 to one side of a magnet 109₁. The other side of the latter is connected by wire 104 to the negative line side 50.

Magnets 109₁—109₈ correspond to magnets of 60 any suitable electrically controlled number representing device and may comprise the apparatus shown in Fig. 5 of the British Patent 372,742 and also herein diagrammatically in Fig. 5.

For each electrical impulse to magnet 109₁ an armature 110 is attracted so that by a pawl 111 and gear 112 a related accumulator wheel or 65 number wheel 113 will be turned a definite amount to represent the numerical values represented by the number of magnetized points of the related steel strip 18.

It will be noted that in the particular construction illustrated by Fig. 5 the number wheel 113 has three zero positions, as indicated by the three 70 notches in its periphery, and said wheel there-

fore has three series of digit numbers (from 0 to 9). The gear 112 and pawl 111 are so constructed that each feed movement of said pawl will advance the gear 112 and wheel 113 one step, and that ten such steps will turn the number wheel 113 from one of its three zero positions to the next. In other words, each feed movement of the pawl 111 will impart one-thirtieth of a revolution to the number wheel 113.

When the operator has visually read from the 10 wheels 113 the record on the strips 18 the wheels are reset to zero by means fully explained in the aforesaid British patent. If a new number 15 changed by some transaction is to be represented upon wheels 113 they may be turned manually, or by a cash register, tabulator, etc., so as to represent a new record. Magnets 109 have suitable wire connections 114 for impulse actuation under control of any suitable machine so as to set 20 wheels to represent a new amount.

It is desirable, further, to neutralize the magnetic effects and thus permit the strips 18 to be remagnetized at points to record the new value. To enter a value to be represented by one or more 25 magnetized points in a series of strips constituting an account device a key 115 (Fig. 3) is depressed. When the key is depressed contacts 89 and 116 will be closed and retained closed by the 30 detent plate 82 acting in the manner described in connection with key 79.

When contacts 116 are closed a wire connection 125 connects the negative line side to one side each of a pair of magnets 126a and 126b. The contact 90e is closed by the cam 90d (Fig. 1) to one side of magnet 190, the other side of this magnet being connected by wire 85 to the positive line side. When magnet 190 is energized the armature thereof pulls a member 193 upwardly so that the pins thereon close contacts 191₁—191₈, which are connected with the positive line side. 40 When magnet 126a is energized the armature thereof pulls a member 127a downwardly so that pins thereon open contacts 180₁—180₈ and close contacts 128₁—128₈ thereby connecting each pair of the related magnets 84 over the contacts 181 45 with the positive line side.

When magnet 126b is energized a member 127b is shifted downwardly and by pins 129 carried thereon contacts 98₁—98₈ are opened and a series of contacts 103₁—103₈ are closed. Such contacts 50 103₁—103₈ close the left side of the series of magnets 84₁—84₈ together so that by a wire 133 one side of all magnets is connected to the negative line side 50.

When magnet 83 (Fig. 4) is energized by closing 55 contacts 80 upon depressing key 115, contacts 14 will be successively closed and opened thirty times as described before. The first twenty steps of the pawl 89 will by means of the cam 91 lower and raise the tube 29, and during this movement 60 the constantly energized magnets 84 will neutralize the magnetic effects of the related steel strips. If so desired, selecting means may be provided so as to energize magnets 84 by a higher voltage to more effectively neutralize the magnetization.

At the end of this movement by the position of cam 90c (Fig. 1) contacts 90e open thereby connecting the magnets 84 through contacts 192 to 70 related contacts 107. Contacts 194 close so that each time the armature of magnet 83 operates by opening and closing of contacts 117, current impulses will be directed from the positive line side to a wire 118 (Fig. 4). The pawl 89 will 75 now be operated ten steps thereby lowering the

tube 28 again and during this time contacts 117 will under certain conditions direct ten impulses to the wire 118.

Considering the control of magnet 100₁, for example, it will be seen that from 118 two paths are supplied, one through upper contacts 108₁ to magnet 100₁, and thence by wire 104 to the negative line side, or by lower contacts 107₁, thence by wire 106 to contacts 102₁ and 128, now closed, thence to magnet 84₁, contacts 103₁, now closed and wire 133 to the negative line side.

As best shown in Fig. 5 contacts 108₁ are opened at zero position of the wheel 113 and contacts 107₁ are closed at the zero position. If the wheel stands at "6" contacts 108₁ are closed and contacts 107₁ opened. Hence, the first four electrical impulses will be directed through contacts 108₁ to the magnet 100₁ so as to give four feed steps to the wheel. As the wheel is now at zero contacts 108₁ open and contacts 107₁ close. Thus the subsequent six electrical impulses will be directed to magnet 84₁ to result in the magnetization of the related steel strip 78 at six points.

During the time the six electrical impulses are being directed to magnet 84₁, cam 91 is being turned clockwise by pawl 69 and in this operation raising the tube 29. The conical points 84a of the various magnets 84 will cause point energizations in accordance with the standing of the accumulator wheels 113. If a wheel stands at "0" each of the ten points of the related strip 78 will receive a point of magnetization and in clearing to set up the representation the wheel will again be turned ten steps to represent "0".

After the amount has been recorded by point magnetizations contacts 95 (Fig. 1) are closed through the action of projection 93' on the disk 94 thus energizing magnet 86 and releasing the depressed key 118 in the manner previously explained in connection with the releasing of key 79.

At the termination of the entry operation key 150 (Fig. 3) is depressed to close contacts 151 thus extending a circuit from the negative line side 50 through the closed contacts 151 to a magnet 152 and thence to the positive line side 46 (see Fig. 4). When magnet 152 is energized it will attract its armature 153 and by means of a slidably mounted member 154 (Fig. 2) integral with the armature 153 a projection 155 will be shifted and since it (Fig. 1) engages holding pawl 71 the latter will be released from one of the teeth of wheel 70.

An extension 156 of pawl 69 is engaged by pawl 71 so as to free pawl 69 from the teeth of wheel 70. As the latter is now free of pawls 69 and 71 it will return to normal under action of return spring 72.

Upon the initial turning of wheel 70 to select a group of record representing devices a projection 157 (Fig. 2) thereof passes away from a plate 158 which is bent at right angles to form a plate 159 which is pivoted at 160 to the base plate 26. Plate 159 therefore permits opening of contacts 161.

When the plate returns to normal, contacts 161 will close and referring to Fig. 4, closure thereof will cause magnet 162 to be energized since key 150 is kept down by the operator to hold contacts 151 closed.

Magnet 162 will attract armature 163 (Fig. 1) to shift an integral slide 164 and a pin 165 carried at its extreme which engages a fork in pawl 51 will release the same from a shoulder 41. By suitable connections such as a pin 166 on pawl

51 engaging pawl 43 the latter may also be shifted. Thus rod 48 and attached parts drop to normal position.

Further, with respect to Fig. 3, it will be seen that depression of key 150 will also rock an extension 63' of the holding pawl 63 to free it from notch 64. Extension 63' will depress a plate 167 so that by means of a stud carried by a curved portion of said plate pawl 56 will be rocked. As plate 56 is now free of both pawls 63 and 56 a suitable spring 168 may return it to normal.

All the operated parts are now at normal in readiness for selecting another group of strips 78 to analyze another record.

By means of a transmitter 170 which also functions as a reproducer the current in magnet 84₁ may be varied according to sound vibrations to record speech upon the correlated strip 78. For controlling such, transmitter 170 has wire connections 171 and 172 to said magnet 84₁. This arrangement permits a magnetization of strip 78 varying with sound vibrations to be recorded by the strip together with point by point magnetizations of the same strip. These sound vibrations are recorded magnetically, and the induced currents produced with the aid of such magnetic record affect only the transmitter. The sound vibrations may be remarks relative to certain accounts, such as "account overdue", and are audible when the value of the account or record is transcribed.

It is understood that in accordance with the nature of the relay magnets 84 and the transmitter 170 any known amplifying means may be employed to amplify the current impulses produced in the coils 84.

The present application is a continuation in part of my earlier application Serial No. 627,458 filed in the United States Patent Office August 4, 1932.

What is claimed is as follows:

1. The method of registering records in an apparatus including several groups of individual magnetic elements which consists in selecting a particular group of individual elements, magnetizing the selected group of individual elements point by point at one or more of definitely located points to represent a record, and then examining a selected group of elements to ascertain which of said definitely located points have been magnetized and thereby obtain an interpretation of the record reproduced by such magnetization.

2. The method of registering records and effecting a subsequent representation of such records which consists in subjecting a group of individual magnetic elements each at definitely located points thereof to a magnetic field to simultaneously magnetize said group of elements at one or more of said definitely located points, and then causing the magnetism at the points magnetized to be converted into electrical impulses each to operate related record representing mechanism.

3. In a machine of the class described, a series of individual magnetic elements, and individual means one for each element capable of effecting by means of electrical impulses the simultaneous magnetization of said elements or of being acted upon simultaneously by the magnetization of said elements to control by induced electric currents certain manifestations to make a visible record of the magnetization of said elements.

4. In a machine of the class described, the combination of a record representing or control element, a magnetic element, electro-magnet means under control of said control element for effecting

the magnetization of said magnetic element at points determined by said control element and thus produce a magnetic record on said magnetic element, and means whereby said electro-magnetic means under control of the magnetized points of the magnetic element causes the control element to manifest a magnetic record previously produced on the magnetic element.

5. In a machine of the class described, the combination of a plurality of groups of devices for representing records, a dialing mechanism, and means under control of said dialing mechanism for transmitting a series of electrical impulses to select a particular group of devices.

10 6. In a machine of the class described, the combination of a plurality of groups of denominationally ordered magnetic elements for representing records, means for supporting said elements in interspersed relationship denominationally, 20 and means capable of magnetizing a selected group of magnetic elements.

15 7. In a machine of the class described, in combination, a group of individual magnetic elements, a corresponding number of electro-magnets, normally out of operative relationship with said elements, means for effecting relative movement between said magnets and said elements to correlate said magnets with said elements in an operative relationship, and means for transmitting a predetermined number of electrical impulses to said magnets while effecting a relative movement between said magnets and said elements to magnetize said elements at predetermined points thereof.

25 8. In combination, a group of elements adapted to have a record impressed on them or control the representation or manifestation of said record, a set of members one for each element and arranged to represent or manifest a record, and 40 selective means whereby said members are adapted to control the production of a record on said elements or said elements are adapted to control the representation or manifestation on said members of the record on said elements.

35 9. In combination, a member adapted to have varying positions, an element adapted to be magnetized at different points thereof, and means for transmitting a definite number of electrical impulses a predetermined number of which, dependent upon the position of said member, effects the magnetization of said element at one or more points thereof.

45 10. In a machine of the class described the combination of several groups of elements adapted to represent records by each being magnetized at one or more points thereof, means for selecting a group of elements, means for magnetizing the selected elements at one or more points, a series of record representing members and means 60 under the control of said members for actuating said magnetizing means to magnetize said elements at one or more points.

55 11. In a machine of the class described, a member adapted to have different positions, an element magnetized at one or more points to represent a record, and means for analyzing said element to cause the position of said member in accordance with the number of points magnetized to represent the same record.

65 12. In a machine of the class described, a magnetic element, a magnetizing device, means for effecting a relative movement between said device and said element to establish a cooperative relation between said device and different portions of said element, and means to energize said

device when it is in cooperative relation with one or more of exactly predetermined points of said element, to effect a local magnetization of such element at one or more of said points.

70 13. In a machine of the class described, a magnetic element, a magnetizing device, means for effecting a relative movement between said device and said element to establish a cooperative relation between said device and a plurality of successive, evenly spaced points of said element, and means to energize said device when it is in cooperative relation with one or more of said points, while leaving such device de-energized at other times, whereby said element will be magnetized locally at one or more of said points.

15 14. In a machine of the class described, a member adapted to have different positions, an element magnetized at one or more points to represent a record, and means for analyzing said element to cause the position of said member in accordance with the point or points magnetized to represent the same record.

20 15. In a machine of the class described, a member having a surface of magnetic material magnetized at one or more points to constitute a magnetic record, a selector responsive to the action of magnetism, means to move said selector into co-operative relation with a selected part of said surface to analyze said magnetic record, and a manifesting device operatively connected with said selector to manifest the indications of said record in accordance with the point or points magnetized.

25 16. In a machine of the class described, a member having a surface of magnetic material subdivided into definite different portions, a magnetizing device, selecting means for effecting relative movement between said member and said device to establish selectively a co-operative relation between said device and predetermined portions selected among said definite different portions of said surface, means for effecting a further relative movement between said member and said device, in a direction different from that of said first-mentioned relative movement, to establish a co-operative relation between said device and different definitely located points of the selected portion of said surface, and means for energizing said device when it is in co-operative relation with one or more of such points.

30 17. In combination, a member adapted to have varying positions, an element adapted to be magnetized at different points thereof, and means for transmitting one or more electrical impulses some of which, dependent upon the position of said member, effect the magnetization of said element at one or more points.

35 18. In combination, indicating means adapted to give different indications, an element adapted to be magnetized at different points thereof, and means for transmitting one or more electrical impulses some of which, dependent upon the indication of said indicating means, effect the magnetization of said element at one or more points.

40 19. In a machine of the class described, indicating means adapted to give different indications, an element magnetized at one or more points to represent a record, and means for analyzing said element to cause the indication of said indicating means in accordance with the point or points magnetized to represent the same record.

45 20. The method of producing a record by magnetic effects and interpreting such record, which consists in repeating a definite electrical current

impulse a predetermined number of times, converting said electrical current impulses into a corresponding number of magnetic effects to produce a magnetic record, and subsequently causing the said magnetic record to produce a manifestation of said record in accordance with said predetermined number of magnetic effects.

21. The method of producing a record by magnetic effects and interpreting such record numerically, which consists in repeating a definite electrical current impulse a predetermined number of times, converting said electrical current impulses into a corresponding number of magnetic effects to produce a magnetic record, and subsequently causing said magnetic record to produce a numerical manifestation of said record in

accordance with the said predetermined number of magnetic effects.

22. The method of producing a record by magnetic effects and interpreting such record, which consists in repeating a definite electrical current impulse a predetermined number of times, converting said electrical current impulses into a corresponding number of magnetic effects to produce a magnetic record, and subsequently causing the said magnetic record to produce, by induction, electrical impulses corresponding in number to said magnetic effects, and utilizing said induced electrical impulses to produce a manifestation of said record in accordance with the number of such induced electrical impulses. 5 10 15
